UNITED STATES PATENT OFFICE.

THEODORE E. YALEY, OF JAMESTOWN, NEW YORK.

APPARATUS FOR CRACKING HYDROCARBONS.

1,329,450.

Specification of Letters Patent.

Patented Feb. 3, 1920.

Application filed April 19, 1917. Serial No. 163,098.

To all whom it may concern:

Be it known that I, THEODORE E. YALEY, a citizen of the United States, residing at Jamestown, county of Chautauqua, and State 5 of New York, have invented certain new and useful Improvements in Apparatus for Cracking Hydrocarbons, of which the following is a specification.

My invention is in the nature of an improvement in apparatus of the above character disclosed in an application for patent filed by me February 19, 1917, and which has been given Serial No. 149,442. Briefly stated, the process of said prior application 15 consists in introducing crude or heavy oil or petroleum in successive spurts into a highly heated retort in which it is immediately converted into vapor and a large percentage thereof cracked or broken up into 20 oil of lighter specific gravity such as gasoline, benzine and the like. From the retort the oil is conveyed through a series of condensers in which the lighter hydrocarbons are separated from the heavier and the liquid 25 from the gaseous. My present invention relates more particularly to the retort in which the oil is cracked and vaporized and one of the condensers by which the heavier hydrocarbons are separated from the lighter. In 30 the accompanying drawings I have shown two of the preferred forms of the invention and described the same in the following specification. It is to be understood, however, that the specific disclosure is for the 35 purpose of exemplification only and that the scope of the invention is defined in the following claims in which I have endeavored to distinguish it from the prior art so far as known to me without, however, relinquishing or abandoning any portion or feature 40 thereof.

Referring to the accompanying drawings, Figure 1 is a diagrammatic view partly in elevation and partly in vertical section showing an oil cracking and refining apparatus embodying my invention and Fig. 2 is a horizontal section showing a modification of a portion of the apparatus.

Referring first to Fig. 1, the retort in 50 which the oil is cracked and vaporized is shown in section at 3 as mounted in a furnace 4 which completely surrounds said retort which is so supported in said furnace by brackets 5 as to provide for the passage 55 of flames and products of combustion completely about the retort so that the latter

may be kept at a high temperature throughout. The furnace is heated in any well known or approved manner, as for example by a burner 6, and the products of combustion are carried off through a vertical stack 7 as is common in this kind of construction. Oil is supplied to the retort from a supply tank 8 through a pipe 9 provided with a ball valve 10 which serves to prevent back flow 65 or the entrance of gases into the tank 8 under the pressure developed by the vaporization of the oil in the retort. The retort shown in Fig. 1 is substantially cylindrical though other forms of retort might be employed. 70

The bottom of the retort is inclined and in the particular construction illustrated in Fig. 1 is conical, rising to a point about the center of the retort as at 11, which point 75 receives the discharge of oil from the pipe 9 through a nozzle 12 connected thereto for this purpose. Thus the oil immediately on its entrance into the retort flows and spreads in a thin film or area over a considerable 80 part of the bottom of the retort, which being highly heated causes the oil to be immediately vaporized and cracked. The vapor from the retort flows upward through the vertical pipe 13 within the flue 7 where 85 its high temperature is maintained by the products of combustion and then upwardly at an incline through the pipe 14 to the worm 15 of the condenser 16.

Obviously, the vapors are more or less 90 cooled as they flow upward through the inclined pipe 14 causing the heavier components of the vapors to be condensed and to flow back into the retort. The length and diameter of the pipe 14 are governed by the 95 proportion of the heavier hydrocarbons which it is desired to return to the still or retort in this manner.

The worm 15 receives the uncondensed vapors from the pipe 14 and being surrounded by a cooling medium, shown as a water filled tank 17, causes a further portion of the heavier hydrocarbons to condense in said coil. Obviously, the heavier liquids are condensed before the lighter liquids and I 105 have found it of advantage to return more or less of the heavier liquids condensed in the condenser 16 to the still to be again submitted to the cracking and vaporizing process. For this purpose I tap the coils of the 110 worm 15 as at 18, 19 and 20, connecting thereto the pipes 21, 22, 23, leading to a

manifold 24. Each of said pipes is preferably provided with a hand valve 25, 26, 27 by which it can be closed off from the manifold 24. Manifold 24 is connected by pipe 28 with the interior of the retort and in the specific construction shown pipe 28 leads to the same nozzle 12 which serves for the pipe 9, a T being used to connect the pipes 9 and 28 and to furnish the outlet opening 12. 5 Obviously the drawoff pipes 21, 22, 23 may be multiplied as desired and by opening the proper valves any desired proportion of the heavier oils may be returned to the still up to the capacity of the condenser for condensing the same. The tap openings 18, 19 and 20 being at the bottom of their respective coils draw off only the condensed liquids, permitting the vapors to pass on. In order to prevent back pressure in the condenser or 15 the rush of gas directly thereto from the retort, I provide a ball valve 30 in pipe 28. 20

From and after the condenser 16 the construction is substantially as described and shown in my said earlier application. The 25 worm 15 is continued in the form of pipe 31 into a closed tank 32 which is more or less filled with oil, the end of pipe 31 being carried along the bottom of tank 32 and perforated as at 33 for the escape of the 30 vapors and any condensed liquid which is carried beyond the condenser 15. The liquid escaping from pipe 31 is of course simply mixed with the oil in the tank, but the vapors escaping from said pipe are more 35 or less condensed in the body of oil 34 therein as they rise toward the surface. The level of the oil in the tank 32 is regulated by an overflow pipe 35 which is swiveled upon an outlet pipe 36 connected to the tank. By 40 swinging the pipe 35 about its swivel joint the height of its upper end and consequently the level of the liquid in the tank may be regulated.

From the tank 32 the uncondensed vapors 45 are drawn by a pump 37 and forced through a second worm 38 in a condenser 39 under a pressure regulated by the pressure reducing valve 40 into a tank 41. The fixed gas is drawn off from said tank from time to 50 time through the valve controlled pipe 42.

The operation of the system has been for the most part described in connection with the description of the apparatus, but may be summarized as follows: The crude or 55 heavy oil flows from the tank 8 through the pipe 9 into the previously heated still or retort where it drips or flows onto the apex of the conical bottom and distributes itself in a thin layer. The heat of the retort 60 which is maintained above the cracking temperature immediately vaporizes the oil therein, causing an instantaneous pressure which temporarily checks the flow of oil from the reservoir and closes the check 65 valve 10. The pressure in the system be-

tween the retort and the pump 37 is, however, normally maintained at about or slightly below the atmospheric and consequently the newly formed vapor, including the lighter hydrocarbons which have been 70 formed by the cracking of the oil, flow into the condenser again reducing the pressure in the still to substantially atmospheric when a further flow of oil takes place from the reservoir and is at once vaporized. The vapor 75 passing up the inclined pipe 14 deposits therein the heaviest components thereof which return down said pipe to the still and are again subjected to the cracking operation and vaporized. The uncondensed vapor 80 from the pipe 14 flows into the condenser 16 and is more or less condensed therein. The condensate or so much of the heavier portions thereof as it is desired to resubmit to the cracking operations is drawn off through 85 the taps provided for that purpose and reintroduced to the still at the nozzle 12. The vapors uncondensed in the condenser 16 and any liquids not drawn off by the taps are introduced through the perforated pipe 33 90 into the bottom of the body of oil 34 with which they are mixed, the liquid portion and the more readily condensable portion of the vapor remaining in tank 32 and the vapor and fixed gases being drawn off through the 95 pipe 43 by the pump 37 and discharged under the back pressure of the valve 40 into the worm 38 of condenser 39 where substantially the remaining condensable portion of the vapors are condensed and collected in the 100 tank 41. As above stated, the fixed gases are drawn off through the valved pipe 42.

Where a still of greater capacity is desired, it is preferably to make it of oblong shape, as shown in Fig. 2, the bottom 44 taking the form of an inverted V in cross section and the oil being distributed at the apex or ridge 45 of the bottom by a longitudinal pipe 46 supplied with oil by a suitable number of pipes 47, 47 connected to the tank 8 110 by a manifold 9'. A pipe 28' connects the longitudinal perforated pipe 46 with the condenser 16 and answers in construction and function the pipe 28 of the form of the device illustrated in Fig. 1. The form of 115 the furnace is of course correspondingly changed.

By my improvement it is possible to quickly distribute the oil over a large area of heated still bottom, thus practically instantaneously vaporizing and cracking the same and maintain the vapors above the cracking temperature for a sufficient length of time to further crack the same by entirely surrounding the still with the hot 120 gases of the furnace and further conducting the gases through the pipe 13 in the flue 7. Obviously the particular forms of still bottoms illustrated are not essential to secure some advantage from my invention, which 130

may be realized provided the still bottom is inclined sufficiently to facilitate the distribution of oil thereover. I have found, however, that the particular forms shown are 5 the most advantageous. Other advantages of my improved apparatus are that the elongated inclined pipe 14 causes the heavier hydrocarbons to condense and flow back into the still for re-treatment and any desired 10 fraction may be returned from the condenser 16 to the still for the same purpose.

I claim:

In a device of the class described a retort, means for heating the retort to a cracking

and vaporizing temperature, a condenser, a 15 vapor pipe leading from the retort to the condenser, a supply tank, a nozzle within the retort, a connection leading from the supply tank to the nozzle and an automatic valve in said connection for preventing access of vapors to the tank, a pipe connecting the condenser with said nozzle for returning condensate thereto, and an automatic 20 valve in said pipe for preventing the movement of vapor under pressure through said 25 pipe to the condenser.

THEODORE E. YALEY.
